DISCHARGE CHUTE FOR STUFFER CRIMPERS
Henry E. Haigler, Jr., and Horace B. Dowell, Jr., Decatur,
Ala., assignors, by mesne assignments, to Monsanto
Chemical Company, a corporation of Delaware
Filed May 23, 1960, Ser. No. 30,839
4 Claims. (Cl. 28—1)

This invention relates to discharge chutes and more particularly to chutes for receiving tow from a crimping device.

In the manufacture of synthetic fibers, a large number of individual filaments are spun simultaneously to form a tow. This tow is then passed through a crimping device which both crimps the tow and cools the tow to set the crimp therein. The tow may then be sold as tow or cut into staple fiber in a well-known manner, after which the staple fiber is carded and drawn into yarn. The purpose of the crimping operation is to increase resistance to relative movement between the staple fibers in the finished yarn. It is well known that the condition of the tow leaving the crimping device has a great deal to do with the quality and appearance of the yarn.

In a conventional crimping device, the heated tow is passed between a pair of rollers which force the tow into a chamber commonly referred to as a stuffing box. A pivoted clapper bar mounted at one end of the stuffing box serves to provide a back pressure against which the rollers operate to thereby fully crimp the tow. When the tow pressure inside the stuffing box exceeds a pre-determined amount, the clapper bar swings aside and the tow passes out of the stuffing box onto a discharge chute. One of the major disadvantages of this conventional equipment is that crimping is not uniform and the cross-sectional configuration of the tow passing through the chute is entirely different from the rectangular cross section that the tow defines in the stuffing box. This is believed to be caused by erratic and excessive back pressures due to erratic feed-in of the crimped tow from the stuffing box to the discharge chute. With this problem in mind, one of the objects of this invention is to provide a novel and improved discharge chute for a tow crimping device.

Another object of this invention is to provide a discharge chute which will uniformly control the back pressure of a crimped tow leaving a stuffing box.

Still another object of this invention is to provide a tow crimping discharge chute which offers a back pressure to rollers feeding the tow into the chute and which will maintain the configuration of the tow leaving the stuffing box.

A further object of this invention is to provide a discharge chute which will receive a crimped tow from a stuffing box without having the tow fold over or depart from the rectangular cross-sectional configuration of the tow in the stuffing box.

A still further object of this invention is to provide a tow crimping discharge chute wherein air pressure is utilized to hold the tow in engagement with a wall of the chute to thereby maintain a substantially rectangular cross-sectional configuration in the tow.

Still another object of this invention is to provide a tow crimping discharge chute wherein the chute itself rather than a clapper bar is utilized to provide a back pressure for the tow being crimped.

One embodiment of this invention contemplates a tow crimping discharge chute wherein a curved chute extends from the lower end of a stuffing box into which the tow is crimped and packed by a pair of crimping rollers. A manifold extending along the chute is provided for drawing air through apertures in the floor of the chute so that

2

when the tow leaves the stuffing box and enters the chute the tow is held tightly in engagement with the floor of the chute to offer a back pressure to the crimping rollers. The air passing through the tow not only cools and sets the crimp in the tow, but also holds the tow against the floor of the chute so that the tow passing through the chute retains its rectangular cross-sectional configuration.

Other objects and advantages of the invention will become apparent when the following detailed description is read in conjunction with the appended drawing in which:

The single FIGURE is a perspective view showing a crimped tow passing through the discharge chute of the present invention.

Referring now in detail to the drawing, there is shown a pair of crimping rollers 11 which force a heated tow 12 into a stuffing box 13. The rollers 11, which are of a conventional design, are rotated at a high speed in a well-known manner so that the tow 12 is crimped and forced into the stuffing box 13, the crimped tow taking on the cross-sectional configuration of the stuffing box. The stuffing box 13 is a conventional type with a rectangular cross-sectional configuration. It is not necessary that the conventional clapper bar be used.

Extending from the lower end of the stuffing box 13 is a chute 14 which curves from a vertical direction at the stuffing box 13 to a horizontal direction. In the stuffing box 13 the tow 12 is crimped and packed into an elongated mass 17 which passes out of the stuffing box 13 onto the chute 14 and along this chute, from which it is picked up in any convenient manner.

A manifold 18 made of sheet metal, is secured to the chute 14 and extends from the upper end thereof substantially along the length of the chute for drawing air through a plurality of apertures 19 in the floor of the chute 14. The flow of air is effected by a fan 20 connected by a duct 21 to a chamber 22 communicating with the manifold 18. The apertured area of the floor of the chute 14 extends from the upper end thereof substantially along the length of the chute.

To insure that a sufficient amount of air flows through the tow at the arcuate upper end of the chute 14, a baffle 25 is mounted in the chamber 22. The baffle 25 extends completely across the chamber 22 and extends upward at one end to the floor of the chute 14. Air which passes through the apertures 19 above the baffle 25 must flow along the baffle toward the arcuate end of the chute 14 until it reaches the free end of the baffle. In effect, the baffle 25 cooperates with the floor of the chute 14 to form an open ended manifold through which air is drawn into the chamber 22, the air passing through the open end. A damper 26 in the duct 21 serves to adjust the rate of air flow.

In operation of the device, the rolls 11 grasp the heated tow 12 and force it down into the stuffing box 13 at a high rate of speed. Because of this high rate of speed, the tow assumes the rectangular cross-sectional configuration of the stuffing box 13. The mass of crimped tow passes downward out of the stuffing box 13 and onto the floor of the chute 14. Since the fan 20 is withdrawing air through the manifold 18 and the apertures 19 in the chute 14, the mass 17 of crimped tow is held tightly in engagement with the chute 14 to provide a uniform back pressure. The tow is pushed downward along the arcuate portion of the chute and then along the horizontal portion of the chute and is taken off the end of the chute in a well-known manner, the air having set the crimp in the tow as it passed along the chute.

The use of this device results in a uniform back pressure and a uniform feeding of the crimped tow from the

stuffing box 13 onto the chute 14. The air passing through the crimped tow into the manifold 18 holds the tow against the surface of the chute 14 to prevent buckling or folding of the tow as it passes along the chute. The tow retains its shape, thereby insuring a superior staple fiber. This also makes packaging of the tow easier, since there is less tangling when the tow has a uniform and tightly packed configuration.

It is to be understood that the embodiment disclosed herein is merely illustrative and that many other embodiments may be contemplated which will fall within the spirit and scope of the invention.

We claim:

1. A discharge chute for a tow crimping device having a stuffing chamber therebelow, comprising a horizontal chute having an arcuate end extending upward to the stuffing chamber, said chute having an apertured floor terminating at the stuffing chamber for engaging a crimped tow emerging from said chamber, a first manifold secured to the arcuate end of the chute in communication with the apertured floor thereof, a chamber secured to the chute beneath the floor thereof and connected to the first manifold, a baffle mounted in the chamber and cooperating with the horizontal portion of the chute to define an open-ended second manifold, a duct leading from the chamber, a fan connected to the duct for drawing air through the apertured floor of the chute to hold the tow against said floor, and means in the duct for adjusting the rate of air flow.

2. A tow crimping device, comprising a stuffing chamber, a pair of rolls mounted adjacent to the chamber for forcing a tow into the chamber, a chute extending downward from the chamber for engaging the crimped tow leaving said chamber, means for controlling the back pressure on the tow leaving the chamber, said means comprising a plurality of apertures in said chute

and means for drawing air through the apertures to hold the tow against the chute.

3. A tow crimping device, comprising a stuffing chamber, a pair of rolls mounted adjacent to the chamber for forcing a tow thereinto, a chute extending vertically downward from the chamber, said chute having a curved upper end terminating in a horizontal portion, said chute being positioned to receive the crimped tow leaving the chamber, means for controlling the back pressure on the tow leaving the chamber, said means comprising a manifold secured to the chute, a plurality of apertures in the chute and suction means connected to the manifold for continuously drawing air through the apertures to hold the tow against the chute.

15 4. A tow crimping device, comprising a stuffing chamber, a pair of rolls mounted adjacent to the chamber for forcing a tow thereinto, a chute having a floor aligned with an interior surface of the chamber for receiving crimped tow from the chamber, said floor having a

20 vertical portion adjacent to the chamber and a curved lower end terminating in a horizontal portion, means for controlling the back pressure on the tow leaving the chamber, said means comprising a manifold secured to the floor of the chute, a plurality of apertures in the 25 floor of the chute, and suction means connected to the manifold for drawing air through the apertures in the floor to hold the tow against said floor.
